His Attorney.

UNITED STATES PATENT OFFICE

HENRY S. WOODRUFF, OF SCHENECTADY, NEW YORK, ASSIGNOR TO GENERAL ELECTRIC COMPANY, A CORPORATION OF NEW YORK

REFRIGERATED OIL BURNER NOZZLE

Application filed December 17, 1930. Serial No. 503,035.

My invention relates to liquid fuel burning apparatus and more particularly the nozzle for spraying fuel into the burner and is an improvement over the device described and claimed in a copending application of A. R. Stevenson, Serial No. 497,519, filed Nov. 22, 1930, and assigned to the same assignee as the present invention.

The apparatus described in the Stevenson application above referred to consists of an oil burner nozzle for spraying fuel into an oil burner. Surrounding and contacting with the nozzle is a casing exhausted and partially filled with a liquid having a low boiling point. A conduit leads from the top part of this casing to a condenser and the condenser in turn is connected to the bottom part of the casing below the level of the liquid therein. In operation the liquid due to the heat of combustion vaporizes, the vapors being carried to the condenser where the heat therefrom is dissipated and absorbed by the condenser and the vapors returned as a liquid to the casing. By this means it is possible to maintain the nozzle at a relatively low temperature during operation, substantially the boiling temperature of the liquid in the casing.

It is the principal object of my invention to provide an improved device of the character set forth above.

In the preferred embodiment of my invention I provide an oil burner nozzle adapted for vertical placement to provide a downwardly directed stream of air and oil into the combustion chamber of an oil burner. The nozzle consists of an inner oil tube provided with an automatically actuated valve. Surrounding this oil tube is a concentric air tube for aspirating the oil from said oil tube to produce a spray of oil and air in a downward direction.

Surrounding the two tubes is a casing from which the air has been exhausted and which is partially filled with a liquid having a low boiling point. Near the top part of the casing on the outside thereof and substantially above the level of the liquid therein are vanes over which a stream of cooling air is directed for absorbing and dissipating the heat from

the vapors which result when the liquid boils during operation of the burner due to combustion conditions. In this manner the vapors are condensed upon the sides of the casing and are returned to the liquid at the bottom of the casing. The arrangement provides a compact and simple structure and eliminates various parts heretofore found necessary.

Referring to the drawings, Fig. 1 shows a cross-section of a preferred embodiment of my invention and Fig. 2 is a section taken along the plane 2—2 of Fig. 1.

Referring to the drawings, the base 10 of the oil burner nozzle is provided with a housing 11 in which is mounted an electromagnetic coil (not shown) for operating the needle valve 12 controlling the opening 13 in the oil tube 14 which is supported by the base 10. Surrounding the oil tube is an air tube 15 which provides a passage for the air to the bottom of the nozzle. Oil is introduced into the oil tube 14 by means of a conduit 16 and air is introduced into the air tube 15 by means of a conduit 17, the base 10 being provided with suitable passages for connecting said conduits and said tubes. When the valve 12 is opened and oil and air are being furnished to the nozzle the passage of the air downwardly between the oil tube 14 and the air tube 15 produces an aspirating effect upon passing through passages 18 between the tips of the two tubes, thus providing a spray of oil from the opening 19 in the nozzle.

Surrounding the oil and air tubes and concentric therewith is the casing 20 also supported by the base 10. The casing has been exhausted through the conduit 21 which is sealed after the liquid 21 having a low boiling point, such as alcohol, or the like, has been introduced into the casing. Due to the fact that the casing has been exhausted the surface pressure upon the liquid 21 is very low which further reduces the boiling point of the liquid.

Connected to the casing 20 at the upper part thereof and substantially above the level of the liquid within the casing are fins or vanes 22 which absorb the heat from the va-

pors produced when the liquid 21 boils upon combustion conditions. Surrounding the casing and the vanes 22 is a second casing 23 supported upon a suitable base 23'. This 5 casing is provided with an air inlet 24, the air being provided to assist combustion within the combustion chamber of an oil burner and providing a stream of cool air for absorbing the heat dissipated by the vanes and 10 carrying the heat thus dissipated through the ports 25 in the base 23' into the combustion chamber of the oil burner. An ignition spark device 26 is also supported by the base 23' and has the function of igniting the oil spray 15 upon starting up the burner. It forms no part of my present invention.

The operation of the device is as follows: Oil and air are introduced into the nozzle by means of the conduits 16 and 17 as pointed 20 out above and a spray is produced from the orifice 19 which is ignited by means of the ignition device 26. Heat from the resulting combustion is radiated to the casing 20 which absorbs the heat and transmits it to the liquid 25 21. Upon boiling, vapors rise from the surface of the liquid 21 and fill the upper part of the casing above the liquid. This heat in turn is absorbed by the walls of the casing and transmitted to the fins or vanes 22. The 30 air passing down through the outer casing 23 which is introduced into the air inlet 24 and passes out of ports 25 absorbs the heat radiated by the vanes and passes it into the combustion chamber. These vanes tend to 35 maintain the casing cool and the vapors coming into contact therewith are condensed and returned to the liquid body 21 as a liquid. Thus the nozzle is maintained at substantially the boiling point of the vapor within the 40 casing.

It will thus be noted that I have provided a compact, self-contained, automatic, self-cooling oil burner nozzle which eliminates the necessity for providing a separate condenser 45 and conduits leading to the same. This makes it possible to more easily manufacture the nozzle, to make it more compact, and to place the whole unit in a most satisfactory position in relation to the oil burner as a whole.

50 The embodiment of the invention illustrated and described herein has been selected for the purpose of clearly setting forth the principles involved. It will be apparent, however, that the invention is susceptible of being modified to meet the different conditions encountered in its use, and I, therefore, aim to cover by the appended claims all of the modifications within the true spirit and scope of my invention.

60 What I claim as new and desire to secure by Letters Patent of the United States, is:

1. An oil burner nozzle having a casing surrounding the same, said casing being partially filled with a liquid having a low boiling 65 point and vanes on said casing for absorbing

and dissipating the heat from the vapors produced when said liquid vaporizes in response to combustion conditions whereby said vapors are condensed and returned to the body of the fluid thereby maintaining said vapors at a relatively low temperature during combustion.

2. An oil burner nozzle having a casing surrounding said nozzle, said casing being partially filled with a liquid having a low 70 boiling point, vanes attached to said casing, and means for directing air against said vanes, said liquid in response to combustion conditions vaporizing, said vanes absorbing the heat from said vapors and dissipating the same whereby said vapors are condensed and returned to the liquid, said nozzle thereby being maintained at a relatively low operating temperature.

3. An oil burner nozzle having a casing surrounding the same, said casing being exhausted and partially filled with a liquid having a low boiling point, vanes attached to said casing, a second casing surrounding said first 80 casing and vanes, and means for directing a stream of air against said vanes, said liquid in response to combustion conditions vaporizing, the heat from the vapor being absorbed and dissipated by said vanes, said vapor being condensed and returned to said liquid thereby thus maintaining said nozzle at a relatively low operating temperature.

4. A vertical oil burner nozzle having an oil tube and an air tube surrounding the same for spraying oil into an oil burner, a casing surrounding said oil and air tubes, said casing being partially filled with a liquid having a low boiling point, vanes attached to said casing, a second casing surrounding said first 90 casing and vanes, for directing a stream of air against said vanes, said liquid in response to combustion conditions boiling and producing a vapor, said vanes absorbing and dissipating the heat from said vapors for condensing the same whereby said nozzle is maintained at a relatively low temperature.

5. A vertical oil burner nozzle having an oil tube surrounded by an air tube for producing an oil spray, a casing surrounding said tubes, said casing being exhausted and being partially filled with a liquid having a low boiling point, vertical vanes attached to said casing at the exterior thereof, a second casing surrounding said first casing and vanes, and means for directing a stream of air into said casing against said vanes, said second casing being provided with ports for providing an exhaust for said air stream, said liquid in response to the heat of combustion boiling and producing a vapor in said casing, said vanes absorbing said heat from said vapors to condense the same, said vanes dissipating the heat from said vapors in said air stream whereby said nozzle is maintained 100 110 120 125 130

at a relatively low temperature during combustion conditions.

6. An oil burner nozzle for providing a downwardly directed spray of air and oil 5 into the combustion chamber of an oil burner including an oil tube provided with a valve, an air tube surrounding said oil tube for producing an aspirating effect to spray said oil, a casing surrounding said oil and air 10 tubes and being concentric therewith, said casing being exhausted and partially filled with a liquid having a low boiling point, vanes vertically mounted on the outside of said casing substantially above the level of 15 the liquid within said casing, said liquid in response to combustion conditions producing a vapor in said casing when said liquid boils, said vanes absorbing the heat from said vapors and condensing the same, a second casing 20 surrounding said vanes and first casing, means for providing a stream of air through 25 said second casing against said vanes whereby the heat absorbed by said vanes is dissipated in the air stream within said second casing, said nozzle thereby being maintained at a relatively low operating temperature.

In witness whereof, I have hereunto set my hand this 16th day of December, 1930.

HENRY S. WOODRUFF.
